UNITED STATES PATENT OFFICE.

EDWIN I. GOLDING, OF NEW YORK, N. Y.

DESIGN FOR A TEXTILE FABRIC OR SIMILAR ARTICLE.

Application filed December 1, 1923. Serial No. 7,934. Term of patent 3½ years.

To all whom it may concern:

Be it known that I, EDWIN I. GOLDING, a citizen of the United States, and a resident of 420 Riverside Drive, in the city, county, and State of New York, have invented a new, original and ornamental Design for a Textile Fabric or Similar Article, of which the following is a specification, reference being had to the accompanying drawing, forming part of this specification.

The figure is a plan view of a piece of a textile fabric or similar article embody-

ing my design comprising groups of squares geometrically arranged, the squares of the different groups being contrastingly colored with reference to the squares of the other groups and with reference to the background.

I claim:

The ornamental design for a textile fabric or similar article as shown and described.

In witness whereof, I have hereunder signed my name this 16th day of November, 1923.

EDWIN I. GOLDING.
